CLAIM

The ornamental design for oven alignment part, as shown and described.

DESCRIPTION

FIG. 1 is a perspective view of an oven alignment part;
FIG. 2 is a first side view thereof;
FIG. 3 is a second side view thereof;
FIG. 4 is a third side view thereof;

(Continued)

FIG. 5 is a fourth side view thereof;
 FIG. 6 is a top side view thereof; and,
 FIG. 7 is a bottom side view thereof.
 Broken lines illustrate features that form no part of the
 claimed design.

1 Claim, 7 Drawing Sheets
